APPAREL APPARATUS

Morris Lazow, Brooklyn, N. Y.

Application May 7, 1937, Serial No. 141,319

4 Claims. (Cl. 38—102)

This invention relates to improvements in apparel apparatus and relates more specifically to a combined trouser hanger and stretcher.

It is one of the objects of the present invention to provide an improved trouser stretcher which may be easily and quickly applied to the garment and which will securely hold the legs of the trousers in a neat and creased condition while at the same time, affording sufficient longitudinal tension to remove wrinkles in the trousers and prevent same from getting out of shape.

Another object of the invention is the provision of an improved trouser stretcher which may be readily adjusted to trousers of different lengths and widths and which will keep the trousers in such a condition as to largely remove the need for pressing same by the application of a hot iron or the like.

Yet another object of the invention is the provision of an improved trouser stretcher consisting of an extensible frame having a trouser crotch engaging portion at one end thereof and suitable trouser cuff engaging clips at the opposite end, which device will support the trousers longitudinally as well as transversely, thereby preserving the shape of the garment over a considerable period of time. Still another object of the invention is to provide a trouser stretcher having improved clips for engaging the cuff portion of the trousers on the inside only, thereby eliminating any possibility of leaving marks upon the material.

In the drawing,

Fig. 1 is a plan view of the preferred embodiment of the invention;

Fig. 2 is a transverse section taken on line 2—2 of Fig. 1;

Fig. 3 is a side elevation of one of the trouser cuff-engaging clips; and

Fig. 4 is a plan view of a pair of trousers supported by the device, a portion of the trousers being broken away.

The presently preferred embodiment of the invention comprises an elongated frame having a pair of extensible members 10 and 11, which members are constructed from a plurality of spaced rods 12. The member 11 is shown as comprising four of such rods which are substantially equally spaced from each other. The two central rods 14 are bent diagonally outwardly at 15 to provide supports 16 for a substantially rectangular member formed from a rod which is curved at 17, which provides the trouser crotch engaging portion. Adjacent to the curved portion 17 on each side thereof are straight portions 18

which extend outwardly substantially the full width of the trousers. This rod is bent back upon itself to form the rectangle and is secured to the wires 14 adjacent to the point 15 by means of welding or otherwise.

The two outer rods 20 of the portion 11 desirably terminate at the point 21 where they are secured by means of welding or otherwise to a substantially U-shaped rod 22, which forms a transverse support for the four parallel rods. The terminals of the rod 22 are secured at 23 to the transverse portion 24 of the rod which constitutes the trouser crotch-engaging portion.

The portion 10 likewise comprises a plurality of longitudinal rods which are desirably mounted in spaced relation in the arrangement shown. The two outer rods 27 are bent outwardly beginning at the points 28 and are welded at their terminals to a transverse rod 29, which is inwardly bent at 30 and is provided with a ring 31 at the center which carries a supporting hook 32. Each terminal of the rod 30 is substantially U-shaped, which U-shaped portion is provided with an elongated base 33 and relatively shorter sides 34. The base portion 33 supports a clip 37 which is adapted to be secured to the cuff portions of the trousers, which clip is provided with a set screw 36 to enable the clip to be adjusted on the base portion to trousers of varying widths. The two central rods 38 are secured at their outer terminals to a transverse rod 39 which, along with another transverse rod 40, maintains the four rods constituting portion 10 in their spaced position.

A side elevation of one form of clip is illustrated in Fig. 3, which clip includes a pair of spaced finger-engaging portions 42, having jaw portions 43 at their lower end. Finger-engaging portions are maintained in spaced relationship by means of a compression spring 44. Each clip 40 is mounted on the elongated base portion 33, which base portion is of somewhat greater length than the width of the clip. Accordingly, the clip is mounted for longitudinal movement upon the base portion and may be secured in the desired place by means of a set screw 46.

At the inner terminal of the portion 10 a transverse bar 50 is positioned, said bar having a plurality of transverse apertures 51 into which the terminals of the several rods are positioned and maintained therein by means of set screws 52. The transverse bar 50 is further provided with additional apertures 53 through which the bars constituting the portion 11 pass, said apertures 53 being of sufficient size to permit free longi-

tudinal movement of the bars constituting the portion 11. The inner terminal of the portion 11 is likewise provided with a transverse bar 55 having transverse apertures 56 through which the bars constituting the portion 10 pass, and additional apertures in which the terminals of the bars constituting the portion 11 are positioned wherein they are secured by means of set screws 57. Thus, the frame may be lengthened or shortened and when the desired length of the extensible structure is attained, the two portions are secured against movement relative to each other by means of set screws 60. To use the device, the entire structure is placed between the legs of the trousers and the curved portion 17 is positioned in engagement with the crotch portion of the trousers. The clips at the opposite end of the structure are then secured to the inside of the cover portion of the trousers, as shown in Fig. 4, and the extensible structure is manually extended until the trousers are sufficiently taut to remove any creases or wrinkles therein. Set screws 60 are now tightened and the entire structure hung by means of the hook 32.

What I claim is:

1. In an apparel apparatus, the combination of an elongated frame comprising a plurality of substantially flat extensible members made from a plurality of elongated rods mounted in spaced relation, one of the members having a concavely curved portion at the outer end thereof adapted to engage the crotch portion of a pair of trousers between the leg portions thereof, the other of said flat members being of sufficient width to engage a substantial portion of the width of the lower portion of the trousers, and being provided with means at its outer end for detachably securing the cuff portions of the trousers.
2. In an apparel apparatus, the combination of an elongated frame comprising a plurality of extensible members, each of the members being

made from a plurality of rods mounted in spaced relationship, one of the members having a curved portion at the outer end thereof adapted to engage the crotch portion of a pair of trousers between the leg portions thereof, the other of said members having means at its outer end for detachably securing the cuff portions of the trousers, said means comprising a transverse bar provided with a substantially U-shaped portion at each terminal thereof and a clip mounted on each U-shaped portion.

3. In an apparel apparatus, the combination of an elongated frame comprising a plurality of extensible members, each of the members being made from a plurality of rods mounted in spaced relationship, one of the members having a curved portion at the outer end thereof adapted to engage the crotch portion of a pair of trousers between the leg portions thereof, the other of said members having a transverse bar at its outer end, said bar extending beyond the edges of the frame, a trouser cuff engaging clip slidably mounted on each terminal portion of said bar and means for securing each of said clips in any desired location on said terminal portion.

4. In an apparel apparatus, the combination of an elongated frame comprising a plurality of extensible members, each of the members being made from a plurality of rods mounted in spaced relationship, one of the members having a curved portion at the outer end thereof adapted to engage the crotch portion of a pair of trousers between the leg portions thereof, the other of said members having a plurality of trouser cuff engaging clips mounted at the outer end thereof, the inner terminals of said extensible members being provided with a transverse bar having a plurality of apertures through which the rods constituting the opposite members pass, and means for securing the extensible members in fixed relationship.

MORRIS LAZOW.
